UNITED STATES PATENT OFFICE.

GEORGE L. ROLLINS, OF FORT WORTH, TEXAS.

COMBINED MILKING PAIL AND STOOL.

1,095,232.

Specification of Letters Patent.

Patented May 5, 1914.

Application filed July 2, 1913. Serial No. 777,101.

To all whom it may concern:

Be it known that I, GEORGE L. ROLLINS, a citizen of the United States, residing at Fort Worth, in the county of Tarrant and State of Texas, have invented new and useful Improvements in Combined Milking Pails and Stools, of which the following is a specification.

This invention relates to combined milking pails and stool and it consists in the novel features hereinafter described and particularly pointed out in the claims.

An object of the invention is to provide a pail with a stool adapted to be supported upon the bottom of the pail and which may be easily and readily removed from the pail when desired. The pail is of the general conventional form but the stool is of especial structure and design. The stool comprises an upper seat portion which is mounted upon converging side walls. A sleeve is loosely mounted in one of the side walls and is resiliently supported at its inner end. This sleeve is provided at its lower side with an opening. A handle is inserted in the said sleeve and is provided with openings. The handle is hollow and carries at its outer end a bowl and a detachable sieve is adapted to be inserted in the outer portion of the handle. The inner portion of the handle is provided with orifices which are adapted to register with the opening in the sleeve.

In the accompanying drawing—Figure 1 is a perspective view of the combined pail and stool, and Fig. 2 is a vertical sectional view of the same.

The pail 1 is of usual or conventional form and is provided with the usual pivoted bail handle 2. The stool comprises a seat portion 3 which is mounted at the upper end of side walls 4, the ends of these walls converge toward each other while the intermediate portions of the walls are bowed away from each other. The walls 4 are provided upon their outer sides with an annular flange 5 which is adapted to lie over the upper edge of the pail 1 when the stool is in position in the pail. The lower edges of the walls 4 are adapted to rest directly upon the bottom of the pail 1. Therefore when the stool is in position in the pail and a person is occupying the seat 3, the weight is transmitted directly through the walls 4 to the bottom of the pail 1 and by reason of the inclination of the said walls 4, the parts are braced and there will be no tendency on the

part of the said walls to bow inwardly toward the center of the pail. A sleeve 6 passes loosely through one of the side walls 4 above the flange 5 and is provided with an exteriorly located collar 7 adapted to bear against the outer surface of one of the said walls 4 whereby the inward movement of the said sleeve with relation to the said wall is limited. The sleeve is provided at its inner end portion and at its lower side with an opening 8 and the said sleeve is provided at its inner end with an eye 9. A spring 10 is connected at its lower end with the eye 9 and at its upper end with the seat portion 3 of the stool. A cross rod 11 is located between the lower portions of the side walls 4 and a spring 12 is connected at one end with the said cross rod and at its other end with the eye 9. These springs are under tension and exert strains against each other whereby the sleeve 6 is held approximately horizontal within the walls 4 or approximately parallel with the seat portion 3.

In combination with the stool and sleeve above described, a dipper is employed and this dipper comprises a hollow handle 13 to the outer end of which is fixed a bowl 14. The handle 13 is provided in the vicinity of its inner end with orifices 15 which are adapted to be brought into register with the opening 8. A conical sieve or strainer 16 is connected with the inner portion of the bowl 14 by means of a flexible member 17 and is insertible in the outer end of the handle 13.

In operation the device is used as follows: The stool is placed in position in the pail and the pail is placed on the ground adjacent the cow so that the handle 13 and the bowl 14 are positioned under the cow. An operator occupies the seat 3 and performs the milking operation. The milk is directed into the bowl 14 from which it flows through the handle 13 into the bucket. The sieve or strainer 16 will catch and retain any particles of foreign substance that might come in contact with the milk while the bowl 14 will serve as a hood and catch or retain any misdirected streams or the quantities of milk which are splashed away from the sieve 16. After one cow has been milked, the operation above described may be repeated at another cow. When the device is moved from point to point, the handle 13 may be slipped out of the sleeve 6 or should the handle 13 be permitted to re-

main in the sleeve and in the event that the said handle or bowl 14 should come in contact with any fixed object or obstruction as the pail is being moved, the sleeve 6 will turn or swing whereby the said handle and bowl can brush by the said objects without having a tendency to displace the stool from the pail. Also by reason of the fact that the sleeve 6 is movably mounted in one of the side walls 4 of the stool, the handle 13 may be disposed at an up or down inclination as desired. The bottom of the bucket is provided with cleats 11' under which the rod 11 may be turned so that the contents of the bucket cannot spill in the event that the bucket is knocked over, as the seat 3 will be held in position over the upper edge of the bucket.

Having described the invention what is claimed is:

1. In combination with a pail a stool adapted to be received within and rest upon

the bottom of the pail and having a seat portion located above the upper edge of the pail.

25

2. In combination with a pail, a stool comprising side walls adapted to rest upon the bottom of the pail, a flange carried by the side walls and adapted to extend over the edge of the pail, and a seat portion which is carried at the upper edges of the side walls.

3. In a device of the character described, a stool, a sleeve movably mounted in the stool and provided with an opening, opposed springs connected with the stool and the sleeve, and a dipper carried by the sleeve.

In testimony whereof I affix my signature in presence of two witnesses.

GEORGE L. ROLLINS.
